[57] **CLAIM**

The ornamental design for a base for a laser alignment tool
, as shown and described.

DESCRIPTION

FIG. 1 is a top view of a base for a laser alignment tool showing my new design;

FIG. 2 is a left side view thereof;

FIG. 3 is a front view thereof;

FIG. 4 is a right side view thereof;

FIG. 5 is a rear view thereof; and,

FIG. 6 is a bottom view thereof.

The broken lines shown in FIGS. 1 - 6 are environmental
only and form no part of the claimed design.
